UNITED STATES PATENT OFFICE.

SHIRLEY L. GOLDSBOROUGH, OF PITTSBURGH, PENNSYLVANIA, ASSIGNOR TO WESTINGHOUSE ELECTRIC AND MANUFACTURING COMPANY, A CORPORATION OF PENNSYLVANIA.

INDUCTION RELAY.

Application filed May 25, 1925. Serial No. 32,544.

My invention relates to relays and particularly to relays of the induction type.

One object of my invention is to provide a reverse-energy relay that shall have means 5 for increasing its sensitivity.

Another object of my invention is to provide an adjustable magnetizable shunt member for the armature of an induction relay to provide exact compensation for the slight 10 unbalancing normally found in the electrical and magnetic circuits of the relay.

In an induction relay of the usual construction having a laminated magnetizable core member with projecting pole pieces on 15 which windings are disposed, the electrical and magnetic circuits are necessarily unsymmetrical to some extent. The effect upon the characteristics of the relay is too slight to cause trouble in most types of relays, but it 20 cannot be ignored in the case of a reverse-energy relay which must operate over a wide range of currents.

It is often desirable to use a reverse-energy relay for the protection of a distribution system 25 in which the short-circuit current may be ten or twenty times the normal full-load current. The relay is provided with a voltage winding and is designed to operate only when the flow of power is in a predetermined 30 direction. If the current winding of the relay or the portion of the core member energized thereby is slightly unbalanced, it is evident that the effect of such unbalance becomes greater under short-circuit conditions, 35 particularly as a short-circuit is usually accompanied by a considerable reduction in system voltage. The result is that the relay operates or does not operate, as the case may be, in a certain direction when the current 40 reaches four or five times the normal value irrespective of the phase relation of the voltage, unless the relay is relatively insensitive.

It has been found that the undesired characteristics of the relay result from a number 45 of causes, such as an unequal number of ampere-turns upon the series pole pieces, an uneven air gap between the upper and lower pole pieces, an armature that is not properly

aligned with respect to the pole pieces, and inequality in the resistances of the electrical 50 paths in the laminated core member. As it is impracticable to attempt to correct each of these causes, I obtain the desired compensation by modifying the flux traversing the armature from the series poles. In accordance 55 with my invention, an adjustable magnetizable shunt member around the armature is disposed adjacent to the series poles. By adjusting this member, the flux traversing the armature may be so modified that no 60 torque is exerted on the same by the current winding alone even when the current is excessive.

For a more complete understanding of my 65 invention, reference should be had to the accompanying drawing, in which

Figure 1 is a diagrammatic view of a relay of the induction type embodying my invention; and

Figs. 2, 3 and 4 are detail views of the 70 magnetizable shunt member shown in Fig. 1.

Referring to Fig. 1, the relay comprises a magnetizable core member 1 having windings 2 and 3 thereon and a movable armature member 4 controlling the co-operating contact members 5.

The relay shown is adapted to be used as a watt or reverse-energy relay, the winding 2 being connected in series and the winding 3 in shunt with an alternating-current circuit. The core member 1 comprises upper pole pieces 6 and 7 and lower pole pieces 8, 9 and 10. The series winding 2 is disposed upon the upper pole pieces and the shunt winding 3 on the lower pole piece 9.

The armature member 4 is a pivoted conducting disc disposed in the air gap between the upper and the lower pole pieces and operated by the magnetic fluxes traversing this air gap and produced by the windings 2 and 3. The armature member 4 should only be actuated when both windings 2 and 3 are energized and the direction and torque of the armature member should depend upon the value and the phase relation of the currents in said windings.

It is found in practice, however, that the magnetic circuits of the windings 2 and 3 are usually slightly unbalanced or the ampere turns upon the upper pole pieces 6 and 7 are unequal so that a torque is exerted upon the armature member 4 when the winding 2 alone is energized. Other conditions may aggravate this effect, such as unequal air gaps between the upper pole pieces 6 and 7 and the lower pole pieces, a faulty alignment of the armature member 4 in the air gap or transverse electric circuits across the laminated faces of the upper pole pieces 6 and 7 that are of unequal resistance.

Since it is impossible to eliminate this unbalancing of the magnetic and electrical circuits of the relay, I provide magnetizable shunt members 11 and 12 mounted on the core member 1 adjacent to the upper pole pieces 6 and 7 to compensate for the torque otherwise exerted on the armature. The shunt members 11 and 12 are pivoted, as shown in Figs. 2 and 3, upon a bolt 13 and may be secured in adjusted position by means of a locking screw 14. As shown in Figs. 3 and 4, the shunt member 12 comprises an L-shaped sheet-metal portion 15 riveted at 16 to a perforated sheet metal portion 17 that receives the bolt 13. The portion 17 of the shunt member is perforated at 18 to receive the head 19 of the bolt 13, the perforation 18 being large enough to permit slight relative movement of the shunt member about the bolt 13. Washers 20 and 21 are clamped between the portion 17 of the magnetizable shunt member 15 and the core member 1, the washer 20 being threaded to receive the locking screw 14.

To adjust the relay, the series winding 2 is connected to a source of current and the voltage winding 3 is open-circuited. A current of 25 or 50 amperes, which is five or ten times the normal value, is passed through the winding 2. The magnetizable shunt members 11 and 12 are then adjusted until the effects of the current poles 6 and 7 upon the armature member 4 balance and no torque is exerted upon the armature member 4 by the energization of the current winding alone. If the voltage winding is then energized, the direction of the torque exerted upon the armature member 4 will depend solely upon the phase relation of the currents in the windings 2 and 3 and the relay will operate properly, even when an excessive current traverses the winding 2 and only a small voltage is applied to the voltage winding 3.

Under normal conditions, the current winding 2 may be traversed by three amperes and the voltage winding 3 may be subjected to 100 volts. Under these conditions, the torque exerted on the armature member 4 is in such a direction as to maintain the contact members 5 open. When the

flow of energy in the circuit reverses, however, the phase relation of the voltage with respect to the current changes and a torque is exerted upon the armature member 4 which tends to close the contact members 5. Since a short-circuit is usually accompanied by a drop in voltage, the relay may be adjusted to operate even when the voltage applied to the winding 3 is reduced to 1 or 2 volts. Furthermore, although the short-circuit may cause the current winding 2 of the relay to be traversed by 50 or 100 amperes, the relay will still operate in accordance with the direction of the flow of energy, since the effect of the current winding alone is accurately compensated by the magnetizable shunt members 11 and 12.

I do not consider that my invention is limited to the precise form shown and described, as it may be applied to relays of other types and the details of construction of the shunt member may be varied without departing from the invention. I do not wish to be limited in scope, therefore, except as limitations may be indicated in the appended claims.

I claim as my invention:

1. An induction relay comprising a magnetizable core member having upper and lower pole pieces, a movable armature disposed between said pole pieces and a magnetizable shunt for said armature extending between an upper and a lower one of said pole pieces.

2. An induction relay comprising a magnetizable core member having upper and lower pole pieces, a movable armature disposed between said pole pieces and an adjustable magnetizable shunt for said armature extending between upper and lower pole pieces and movable with respect to one of said pole pieces.

3. An induction relay comprising a magnetizable core member, current and voltage windings thereon, a movable armature actuated thereby in accordance with the phase relations of the currents traversing said windings and an adjustable magnetizable shunt about said armature and pivotally mounted upon the core member.

4. An induction relay comprising a magnetizable core member having projecting pole pieces, an armature member adjacent said pole pieces, an L-shaped magnetizable shunt member pivotally mounted on said core member and controlling the flux traversing said armature member and means for securing said shunt member in desired position.

5. An induction relay comprising a one-piece magnetizable core member having upper and lower projecting pole pieces, an armature member disposed between said pole pieces, and an L-shaped magnetizable shunt member pivotally mounted on said

core member on each side of said upper pole pieces and extending adjacent thereto.

6. An induction relay comprising a one-piece magnetizable core member having two upper and a lower projecting pole pieces, an armature member disposed between said sets of pole pieces and means for so shunting the magnetic flux between the

sets of pole pieces from the armature member that the armature is precluded from 10 operating except by the cooperation of the magnetic flux produced by both sets of pole pieces.

In testimony whereof I have hereunto subscribed my name this 14th day of May, 1925.

SHIRLEY L. GOLDSBOROUGH.
